UNITED STATES PATENT OFFICE

114,846

DESIGN FOR A LAMP BASE

James Kernes, Chicago, Ill.

Application April 10, 1939, Serial No. 84,164

Term of patent 3½ years

To all whom it may concern:

Be it known that I, James Kernes, a citizen of the United States of America, residing in the city of Chicago, in the county of Cook and State of Illinois, whose postoffice address is 417 South Jefferson Street, Chicago, Ill., have invented a new, original, and ornamental Design for Lamp Base, of which the following is a specification, reference being had to the accompanying drawing, forming part thereof.

In the accompanying drawing, Figure 1 is a side elevational view of the lamp base showing my new design.

I claim:

The ornamental design for a lamp base, substantially as shown.

JAMES KERNES.
